UNITED STATES PATENT OFFICE.

ABRAHAM B. KOPLIN, OF HELLERTOWN, PENNSYLVANIA, ASSIGNOR TO
HIMSELF AND JEREMIAH S. HESS & BRO., OF SAME PLACE.

STREET-CURB.

SPECIFICATION forming part of Letters Patent No. 379,401, dated March 13, 1888.

Application filed June 29, 1887. Serial No. 242,875. (No model.)

To all whom it may concern:

Be it known that I, ABRAHAM B. KOPLIN, of the borough of Hellertown, in the county of Northampton and State of Pennsylvania, have 5 invented a new and useful Improvement in Street-Curbs, of which the following is a full, clear, and exact description.

This invention consists in a metal curb of novel construction for street-pavements, substantially as hereinafter described, and pointed out in the claims.

Reference is to be had to the accompanying drawings, forming a part of this specification, in which similar letters of reference indicate 15 corresponding parts in all the figures.

Figure 1 represents a view in perspective of two attached sections of a street-curb embodying my invention and as adapted to a brick pavement. Fig. 2 is a plan of the same as applied to the pavement, and Fig. 3 is a vertical transverse section of like parts. Fig. 4 is a transverse section of a pavement, showing a modified construction of the curb and special means for securing it.

25 The curb is made of either cast or wrought iron and of a width or depth dependent upon the depth of the gutter, it being designed to project one inch or more below the top of the gutter-cobble *b*. It is built up in sections *A* of any desired length—say ten feet, more or less—and the sections united as by fish-plates *c*, or otherwise. Said curb is mainly of double-flange shape—that is to say, is constructed with an upper approximately horizontal flange, 30 *d*, and an outer downward flange, *e*, arranged to form an obtuse angle with the upper flange. These flanges extend throughout the length of the curb-sections, the outer one, *e*, passing below the top of the cobble of the gutter, and 35 the other flange, *d*, being on a level with the pavement, or thereabout. When the pavement *B* is a brick one, as shown in Figs. 2 and 3, then I sometimes construct the flange *d* of the curb, or each curb-section, with angular 40 pockets or recesses *f*, to receive a portion of each outer paving-brick within it. For a stone pavement said flange *d* may be made plain along its inner margin. The gutter-flange *e* is of a diminishing thickness in a downward direction and joins the upper flange by an interior concave molding.

The sizes and thicknesses of the different parts may be varied to suit circumstances or different opinions, and accordingly as the curb is made of cast or wrought iron.

55 As shown in Figs. 1 and 3, the flange portion *e* of the curb is provided with legs or feet *g*, which are of sufficient length to project considerably into the ground below the cobblestones of the gutter, and may be made flaring 60 at their lower ends, as shown, to give a more efficient anchoring effect on the curb. In Fig. 1 these legs or feet *g*, of which there may be two or more to each section, are shown as cast to or with the curb sections, and in Fig. 3 they 65 are shown as separately secured thereto by a lap-joint and bolts; but they may be otherwise attached.

Fig. 4 shows the invention as applied to a stone or flag pavement, *B'*, and with the feet 70 *g* omitted, in which case tie-rods *h* are used in place of the feet, said rods, of which there may be two to each section, being fastened at their one end to the inside of the curb, and, after passing through the ground beneath the pavement to the building-line, being secured at their other end to the wall *C* of the building. By means of this metal curb a curb extending the full length of a "block" or square may be laid and will be sure to remain in position. 75 It cannot be undermined with water, as in the case of stone curbs, in which latter instance the water soaks down to the bottom of the trench dug for reception of the curb and then runs along beneath the curb and saps its 80 foundation, which causes the curb to sink out of line or position. With my improved curb, however, no trench is necessary, but, at the best, only holes to admit the legs or feet, and where tie-rods are used instead of legs or feet 85 even these holes are not necessary.

The improved curb is easy of adjustment, and may be put down at a much less expense than a stone curb.

A brick pavement is less expensive and better with my improved curb than with the ordinary curb, inasmuch as the bricks need not be cut at the outer margin of the pavement to fit the curb by reason of the angular pockets or recesses *f* in the top of the curb, which serve 90 to admit approximately one-half of the several outer bricks within them, as shown in Fig. 2.

Frost will not affect this curb, because when legs or feet *g* are used they are planted in sand, *i*, as shown in Fig. 3, and when tie-rods *h* are used they also lie in said sand *i* beneath the 5 pavement, and with sand there is no tendency to heave up. Moreover, this curb or curbing is applicable to all climates and much cheaper than a stone one, and when coated with red lead before laying it down it is as durable as 10 a stone curb and can be shipped at less expense. Said curbs, too, present a better appearance and possess great strength, so that there is little or no danger of their being broken by the backing of heavily-loaded vehicles 15 against them.

Having thus described my invention, what

I claim as new, and desire to secure by Letters Patent, is—

1. The metal curb-sections A, having an inner top flange, *d*, provided with angular 20 pockets or recesses *f* along its inner margin and with an outer downwardly-projecting gutter-flange, *e*, essentially as described.
2. A metal curb-section, A, having an inner top flange, *d*, an outer downwardly-projecting 25 gutter-flange, *e*, and legs or feet *g*, substantially as and for the purposes herein set forth.

A. B. KOPLIN.
